UNITED STATES PATENT OFFICE.

HARRY C. MONTGOMERY, OF CLEVELAND, OHIO.

DESIGN FOR A SOLE FOR BOOTS OR SHOES.

SPECIFICATION forming part of Design No. 22,326, dated April 4, 1893.

Application filed February 25, 1893. Serial No. 463,761. Term of patent 14 years.

To all whom it may concern:

Be it known that I, HARRY C. MONTGOMERY, a citizen of the United States, residing at Cleveland, county of Cuyahoga, and State of Ohio, have invented and produced a new and useful Design in Detachable Soles for Boots or Shoes, and the following is a specification thereof, reference being had to the accompanying drawings, which show my newly-designed sole.

Figure 1 is a perspective view of my new design in detachable boot or shoe soles, and Fig. 2 is a cross section thereof.

The design consists more especially in the configuration of the sole when viewed from the bottom, substantially as shown in Fig. 1.

5 A represents the flat surface of the web of the sole, which comes next to the sole of the shoe, and B the continuous and unbroken rib which stands out from the said web as shown and forms the lower or wearing surface.

The design I wish to cover comprises the configuration represented by the surface A, of the web, the flat surface b, the plain outside edge c of said rib, and the inclined or beveled inner surface d thereof, the said rib B with this outline of surface having the shape of the edge of the sole of a boot or shoe at the sides and front and rear thereof. 25

Having thus described my invention, what I claim as new, and desire to secure by Letters Patent, is—

The design for detachable soles for boots and shoes, substantially as shown and described.

HARRY C. MONTGOMERY.
